United States Patent Office.

H. M. HALL, OF DANBY, VERMONT.

Letters Patent No. 88,630, dated April 6, 1869.

IMPROVEMENT IN ATTACHMENT FOR SEWING-MACHINE.

The Schedule referred to in these Letters Patent and making part of the same.

To all whom it may concern:

Be it known that I, H. M. HALL, of Danby, in the county of Rutland, and State of Vermont, have invented a new and improved Attachment for Sewing-Machines; and I do hereby declare that the following is a full, clear, and exact description thereof, which will enable those skilled in the art to make and use the same, reference being had to the accompanying drawings, forming part of this specification, in which—

Figure 1 is a plan view of the attachment, with its rods, or fingers removed.

Figure 2 is a longitudinal vertical section of the same, through the line $x x$ of fig. 1.

Figure 3 is a cross-section of the same, through the line $y y$, fig. 1.

Figure 4 is a detail view of one of the fingers, showing the disk and head of the same.

The figures, from 5 to 13 inclusive, illustrate the different combinations of the fingers, for the different kinds of work to be done.

Similar letters of reference indicate corresponding parts.

The object of this invention is to provide an attachment for sewing-machines, which, by the permutation of its devices, will hold, or guide the goods in any one of the several operations, such as (among others) the operations of seaming, binding, braiding, tucking, and marking, gathering, hemming, quilting, stitching, and others.

The attachment consists, in general terms, of a plate, having holders, or standards, by means of which two or more slender rods, or fingers (some of which have peculiar devices contributing to their functions) are adjusted, and held in the proper position for performing such functions.

The fingers are, preferably, of metal, and are about the size of large knitting-needles, some being plain fingers, while others are provided with accessory devices, which conduce to the peculiar office required, which, with other devices perfecting the whole, will hereinafter be more fully set forth.

In the drawings—

A is the base-plate of the attachment, which is to be affixed, preferably, to the gauge-plate of the sewing-machine, or directly to the cloth-plate of the same, in which latter case, the upturned part E serves as a gauge for the goods to pass against, while the attachment is on the sewing-machine.

The plate is provided with two perforated standards, C and D, through which the fingers pass, the latter being arranged one above the other, and project over the cloth-plate in suitable proximity thereto.

The rear standard C is fixed, while the front standard D is movable to or from the fixed standard, in order to cause the divergence or convergence of the fingers held in the holes of the standards, for a purpose to be shown.

The standard D and plate A may be constructed in any suitable manner, to permit the said standard to be moved, but I prefer, as the simplest mode, to double over the edges of the plate A, as shown at B, so as to form grooves for the flanches a , of the two standards, to rest in, and to serve as guides for the flanch of the movable standard, the standard C being fixed stationary, by means of screws, or rivets passing through its flanch and the parts B.

The standards are formed with a series of perforations, 1 2 3, &c., arranged in line, one above the other, and all in the same vertical plane, so that the fingers, passed into any of these holes, will project out through the vertical slot in the gauge E, and project over the cloth-plate I, on, or over which the plate A is fixed.

The general arrangement of the fingers will be better understood by reference to the several figures, from 5 to 13, where the particular fingers required are shown in proper combination for the work to be done.

In order to hold the fingers firmly in place, the rear standard is made hollow, and contains any elastic substance, as cork, or rubber, which, from its contractile character, clasps the fingers, and thus prevents their accidental slipping while in use.

I prefer to use cork, as it is a material which exerts the best frictional effect on the fingers.

There should be an additional hole in the front standard to the finger-holes, and which is in line with the upper hole in the rear standard, for a purpose to be shown.

The holes in the movable standard should be nearer tight than those in the fixed standard, so that when the former is moved toward the latter, the fingers will be converged toward each other, whereby the outer ends of the said fingers will bear upon the goods, or fabric between any set of two or more of the fingers, and thus hold and guide the same with the proper resistance outside, or beyond the line of draught, or cloth-feed of the sewing-machine.

It will be observed, that either standard may be made the movable standard; that is to say, the standard C may be movable while the standard D is fixed, in which case the former must be made to approach the latter, in order to converge the fingers, the relative number and arrangement of the finger-holes remaining as before.

The plate A is formed with a mortise, d , extending crosswise of the plate, just behind the gauge E.

The mortise is for the reception of the tongue G; projecting from the part H, which latter may consist of a slotted plate, or of a wire bent double, to obtain a longitudinal opening analogous to and serving as a slot for the clamp-screw, or screws, which fix it to the cloth-plate, or the usual gauge of the sewing-machine, if desired.

It will be observed, that the plate A may be adjusted laterally on the tongue G, in order to bring the

fingers at the proper distance from the needle, which is represented by the red dot *b* in fig. 1, showing the general relative position of the fingers and gauge *E*, with reference to the needle of the sewing-machine, when the attachment is in use.

This mortise *d* may be formed in any suitable manner, or may consist of two or more wire loops, bent, and affixed to the plate *A* in a manner to receive the tongue *G*; or the plate *A* may be bent to form a recess for the tongue, which may be covered by a plate; or a portion of the upturned edges *B* may be cut away to admit the tongue; or the tongue may be slotted, and affixed to the plate *A* by means of a clamp-screw passing through the slot, and working in the base-plate; but all of these different modifications would be simply mechanical equivalents of the device which I prefer to use for this purpose, as being, perhaps, the simplest and easiest made, and which is, to cut away the upturned edges *B*, just in rear of the gauge *E*, to the required distance, and affixing at this part a plate, *c*, bent as shown, and affixed, either by rivets or solder, to the gauge *E*, and to the base-plate, as shown.

The object of this device is to enable the base-plate to be held in the proper position above the cloth-plate, without being attached thereto, when certain operations, or the construction of certain machines require it, in which case the part *H* will be clamped to some fixed part of the machine, which lies above its cloth-plate.

The fingers are plain, slender, cylindrical rods, preferably of steel.

One end of the fingers is provided with devices conduced to certain specific functions.

These devices consist, in general terms, of heads, disks, a pencil-holder, a cross-bar, or stop-bar, and a quilting-point.

For convenience, and to reduce the number of separate parts, these devices are applied on, or near one end of the fingers, while the other ends are available as plain fingers, when such are required.

This combination reduces the number of separate fingers to only five, with which they are made to assist the sewing-machine in twelve or thirteen different operations.

Two of the fingers bear, each at one end, a cylindrical cap, *e*, as shown.

To each of these caps is affixed, by solder or otherwise, a disk, or button, *f*, which is placed back from the rounded end of the cap.

One of such fingers is shown in the detail view of fig. 4, and these fingers will be called, in succeeding description, "the head-fingers," or "disk-fingers," according as either device is employed to perform its particular function, in combination with other fingers, or together simply.

When the plain ends of any of the fingers are employed in such combinations, they will be denominated simply as plain fingers, as the devices which they bear at their other ends will not then be in use.

The cross-bar finger *g* is provided with a short wire cross-bar, *h*, affixed to it at a short distance from one end, as shown in the several figures, 5, 6, 8, 9, 12, in a portion of which figures the cross-bar is, however, not in use, its finger *g* merely serving as a plain finger.

The marking-finger *i* is provided with a pencil-holder, *j*, which is a plate, affixed to one end, and provided with a screw, *k*, to protrude the pencil-point, located in the same hole, as shown in dotted outline.

The upper part of the plate *j* is formed with a recess, for inserting the end of one of the plain fingers, in order to steady the said plate and its contained pencil, and the additional hole in the front standard, as before mentioned, is to receive this finger.

The remaining finger, *l*, has a bent arm, *m*, to serve as a guiding-point in quilting, which will be more fully described hereinafter.

The several combinations of these different fingers, which are employed for certain operations, will now be specially described by reference to the several figures, from 5 to 13 inclusive.

Fig. 5.—To sew several pieces in one seam.

In this combination plain fingers only are used, one more finger being taken than there are pieces of cloth to be run together.

The cloth is inserted between the fingers, as shown by the red lines, with the edges to the gauge-face, which can be set out any distance required for width of seam.

When this is done, the machine is started, and the cloth will run alike on the edge, if the work is not permitted to drag, which should be kept loose in front of the gauge.

If light work is being done, it will run by itself much better than when assisted by the operator.

Should any of the pieces be inclined to double at the edge, withdraw the finger just above it.

Fig. 6.—To make a seam for felling with uneven edges.

Two plain fingers, with the barred finger *g* *h* between them.

First plain finger in first holes; barred finger next above; second plain finger next above the barred finger; the bar *h* projecting upward, and distant from the gauge *E* as far as the under strip of cloth is to project beyond the upper.

Set the gauge for width of seam, and have the needle catch both pieces of cloth.

Remove the work when sewed, and fell it down by hand, or with the feller, or hemmer, on the foot of the machine.

Fig. 7.—To put on a staying or bias-piece.

Several plain fingers, (according to the number of pieces,) and a head-finger, *e*; the plain fingers below, and the head finger on top.

Place the goods between the plain fingers and the staying, in the space between the shoulder of the cap, or head, and the gauge *E*.

This space can be made any reasonable width, by pushing out the fingers.

Insert the goods, as shown by the red lines, and converge the fingers, by moving the standard *D*, as before described.

Fig. 8.—To put on braid by twice sewing.

One plain finger, the barred finger *g* *h*, and headed finger *e*, arranged as shown, with the bar *h* turned downward, and about one-half the width of the braid distant from the gauge.

The head *e* is placed from the gauge the width of the braid.

The goods are inserted below the barred finger, with the edge against the bar *h*.

After being sewed, the braid may be turned by hand, or between any two of the fingers.

Fig. 9.—Sewing on braid at any distance from the edge.

Plain finger below, barred finger next above, and head finger next above that.

The bar *h* is turned upward to enclose the braid between it and the head *e*.

The cloth is placed between the plain finger and the barred finger.

The bar *h* is set out from the gauge *E* the distance to which the braid is to be put on from the edge of the cloth which runs against the gauge.

The bar *h* is set from the head the width of the braid.

Should it be required to put on braid over two inches from the edge, the plate *A* will have to be held from above, so that the work can go under to any desired

distance, instead of being between the plain finger and the barred finger.

The work can then be gauged by inserting the finger *l*, and turning down the arm *m* as a guide.

I will here note that when the heads are used as above, the disks are to be turned upward out of the way.

Fig. 10.—Binding.

The two disk-fingers *f f*, with the disks, turned face to face, and distant from the gauge half the width of the braid.

The cloth is placed between the heads *e*.

The lower finger should be placed in the first holes, and the upper one in the third holes.

The gauge should be arranged to extend along the side of the presser-foot, as far as the needle, or the binding will slip out before it gets to the needle.

The binding should be caught in the work just as it is to be done, and to slip between the heads, taking care to have the edges of the braid in the space between the disks.

Either lip of the binding can be made the longest, by placing one head nearer the gauge than the other.

Fig. 11.—Hemming.

Plain finger below, head finger above, with the head as far from the gauge as the width of the hem is to be.

Then turn an inch or two on the work, and slip it in the space left between the head and gauge.

The fingers should be made to pinch somewhat harder than in seam-sewing.

Fig. 12.—Gathering, or ruffling.

Head finger at the bottom; two plain fingers above.

The goods to be ruffled are placed in the space between the head *e* and gauge.

Lengthen the stitch, and make a tension on the upper thread, and the goods will ruffle as they pass through the fingers.

If to be sewn on at the same time, place the straight piece above the ruffled goods, with another plain finger above it, and converging the finger with the standard *D*, in the usual manner.

Fig. 13.—Tucking and marking.

One plain finger at the bottom, the pencil-holder *j* next above, and a plain finger in the two upper holes of the standards, with its end inserted in the hole, or recess in the plate *j*, to steady it.

The pencil-plate is set as far out from the gauge as the width of the tuck.

The gauge *E* is to be set the width of the tuck from the needle, and alongside of it, to prevent variation after leaving the fingers.

Quilting.

Hang the plate from above, and run the work under, using the arm *m*, of the finger *l m*, as a guide to follow the previous seam.

It will be observed, that in each of the above combinations, the fingers must be converged, so as to pinch the goods held between them.

I claim as new, and desire to secure by Letters Patent—

1. The combination, in a sewing-machine attachment, of a plate, *A E*, having a fixed standard, *C*, and a movable standard, *D*, with a series of fingers passing through the said standards, substantially as and for the purpose herein shown and described.

2. The hollow standards, filled with cork, rubber, or other elastic matter, in combination with the guide-wires, substantially as and for the purpose herein set forth.

3. The part *H*, having a tongue, *G*, in combination with the plate *A*, and fixed and movable standards, *C* and *D*, substantially as and for the purpose herein shown and described.

4. The combination, in a sewing-machine attachment, of the two head and disk-fingers, *e f, e f*, as shown at fig. 10, substantially as and for the purpose set forth.

5. The combination, in a sewing-machine, of the pencil-holder finger *j i*, and two plain fingers, as shown at fig. 13, substantially as and for the purpose set forth.

The above specification of my invention signed by me, this 20th day of October, 1868.

Witnesses:

H. M. HALL.
